Fig. 1.

Fig. 2.

Fig. 3.

Fig. 4.

Fig. 5.

Fig. 6.

FIGURE 1 is a perspective view of a foldable traversing screen according to a first embodiment of my new design;

FIGURE 2 is a perspective view on a larger scale of the repeating pair of complementary blocks from which the foldable traversing screen of FIGURE 1 is assembled;

FIGURE 3 is a perspective view of a foldable traversing screen according to a second embodiment of my new design;

FIGURE 4 is a perspective view on a larger scale of one of the repeating individual blocks from which the foldable traversing screen of FIGURE 3 is assembled;

FIGURE 5 is a perspective view of a foldable traversing screen according to a third embodiment of my new design; and

FIGURE 6 is a perspective view on a larger scale of the repeating pair of complementary blocks from which the foldable traversing screen of FIGURE 5 is assembled.

The rear of each of the screens illustrated is substantially the same as the front thereof shown except in reverse and is therefore not shown.

This application is a continuation of Serial No. D. 68,643, filed February 5, 1962 for "Foldable Traversing Screen"; Serial No. D. 68,749, filed February 9, 1962 for "Foldable Traversing Screen"; and Serial No. D. 68,752, filed February 9, 1962 for "Foldable Traversing Screen" which are now abandoned applications.

I claim:

The ornamental design for a foldable traversing screen, substantially as shown and described.
